Primary Examiner — T Chase Nelson*(74) Attorney, Agent, or Firm* — Sterne, Kessler, Goldstein & Fox P.L.L.C.**CLAIM**

The ornamental design for a shoe, as shown and described.

DESCRIPTION

FIG. 1 is a bottom perspective view of a shoe showing the claimed design;

FIG. 2 is a top plan view thereof;

FIG. 3 is a bottom plan view thereof;

FIG. 4 is a side view thereof;

FIG. 5 is another side view thereof;

FIG. 6 is a front view thereof; and,

FIG. 7 is a rear view thereof.

The broken lines in the figures show portions of the shoe that form no part of the claimed design.

1 Claim, 6 Drawing Sheets See application file for complete search history.
